WITNESSES:

John E. Hobbs.

INVENTOR:

UNITED STATES PATENT OFFICE.

JOHN E. HOBBS, OF NORTH BERWICK, MAINE.

DESIGN FOR A HUB-RUNNER.

SPECIFICATION forming part of Design No. 22,912, dated November 14, 1893.

Application filed October 23, 1891. Serial No. 409,622. Term of patent 14 years.

To all whom it may concern:

Be it known that I, JOHN E. HOBBS, a citizen of the United States, residing at North Berwick, in the county of York and State of Maine, have invented and produced a new, useful, and original Design for Hub-Runners, of which the following is a specification, reference being had to the accompanying drawing, forming part thereof, and being an elevation of my design for an attachable runner.

The leading feature in my design is the cap-bar of the runner provided with a depression beginning at a point about one-third to one half the length of the runner from the tip of the nose or forward end, and extending forward at an oblique angle to the line of the base-bar till it comes near the shoe, and then continuing approximately concentric therewith to the nose of the runner or point of junction with the shoe, the fore part of the runner thus being shaped like the lower seg-

ment of an ellipse cut off at the longer axis. The cap bar passes back to an enlarged portion A which is supported by the upright B and stands at the junction of the two braces 25 D, D.

In the figure, S is the shoe, C the cap-bar, p, p, p, interposed pieces occupying the space between the shoe and cap bar, N the curved or upturned neck or nose, the whole presenting to the eye the outline or contour of a short-bodied sleigh runner, with long base-bar, or runner proper, elongated forward in the form of a semi-ellipse, substantially as represented in the drawing. 35

What I claim is—

The design for a hub runner herein shown and described.

JOHN E. HOBBS.
